UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN-SPEED-CONTROL DEVICE.

1,355,189.

Specification of Letters Patent.

Patented Oct. 12, 1920.

Application filed November 21, 1919. Serial No. 339,604.

To all whom it may concern:

Be it known that I, THOMAS H. THOMAS, a citizen of the United States, residing at Edgewood, in the county of Allegheny and State of Pennsylvania, have invented new and useful Improvements in Automatic Train-Speed-Control Devices, of which the following is a specification.

This invention relates to mechanism for controlling the speed of a train according to the traffic conditions.

In various types of train speed controlling equipments, a governor device is employed, which is responsive to the speed of the train for operating mechanism by which the speed of the train is regulated or controlled.

If the governor device should fail to function, as by the breaking of the governor shaft, for example, then it will be evident that the speed control apparatus will not be operative to limit the speed of the train.

The principal object of my invention is to provide means for limiting the speed of the train to a predetermined degree upon failure of the speed governor device.

In the accompanying drawing, the single figure is a diagrammatic sectional view of a train speed controlling apparatus embodying my invention.

As shown in the drawing, the train speed controlling apparatus may comprise a governor device 1, operated according to the speed of the train for controlling mechanism by which the speed of the train is regulated, a brake application valve device 2, an additional governor device 3, and a magnet valve device 4.

The governor device 1 may comprise governor balls 5, rotatable with a member 6, which is operatively connected to an axle or other rotating part of the vehicle, so that the governor balls are rotated at a speed proportional to the speed of the train.

Within the member 6 is mounted a sleeve 7 having a flange 8 adapted to engage the arms 9 of the governor balls 5, and within the sleeve 7 is mounted a governor shaft 10.

Outward movement of the governor balls 5 by centrifugal action due to the rotation

of member 6, according to the speed of the train, tends to move the sleeve 7 and shaft 10 in one direction, while a coil spring 11 acts on said sleeve to oppose this movement and tends to move the sleeve in the opposite direction. 55

Attached to the shaft 10 is a crosshead 12, which is adapted to operate mechanism for regulating the speed of the train, such as that disclosed in the prior Patent No. 1,316,205 of Walter V. Turner dated September 16, 1919.

The brake application valve device 2 may comprise a casing, having a piston chamber 13, containing a piston 14, and a valve chamber 15, connected by pipe 16 to a source of fluid under pressure and containing a slide valve 17, adapted to be operated by piston 14. 65

The slide valve 17 controls the venting of fluid from the usual brake pipe 18, a reduction in pressure in which is adapted to effect an application of the brakes in the well known manner. 70

The electro-magnet of the magnet valve device 4 is adapted to operate a valve 19 which controls communication from piston chamber 13 through pipe 20 to a pipe 21. A vent valve 22, adapted to be operated by an adjustable tappet 23, carried by cross-head 12, controls the venting of fluid under 75 pressure from pipe 21 to the atmosphere. 80

The governor device 3 controls the electric circuit of the magnet device 4 and may comprise governor balls 24 connected to a member 25 which is operatively connected to the car axle so as to rotate at a speed proportional to the speed of the train. 85

The governor balls 24 act on a stem 26, carrying at one end a contact ring 27 for closing the circuit of the magnet device 4. 90

The magnet circuit contains a source of current 28, and when the speed of the train is less than a predetermined degree the contact 27 closes the magnet circuit, so as to energize the magnet device 4 and thereby hold the valve 19 closed. 95

In operation, if the train is running, and the speed of the train be increased above a predetermined degree, the governor balls 24 will operate the shaft 26 so as to open the 100

circuit of the magnet device 4 and thus permit the valve 19 to unseat. Communication is thereby established from pipe 21 to pipe 20, but if the speed governor device 1 is operative, the valve 22 will be closed, by the operation of the governor balls 5, which cause the shaft 10 and the crosshead 12 to be shifted outwardly, so as to move the tappet 23 away from the valve 22.

10 If, however, the governor should fail, due to breakage of parts or otherwise, since the governor balls then cease to rotate, the spring 11 will shift the shaft 10 and the crosshead 12, so that the tappet 23 will act 15 to open the valve 22.

If the speed of the train exceeds a predetermined degree at the time the speed governor 1 fails, the circuit of the magnet device 4 will be open, so that the valve 19 establishes communication from pipe 21 to pipe 20.

It will now be seen that under the above conditions, fluid under pressure will be vented from piston chamber 13 of the brake application valve device 2, so that piston 14 will operate the valve 17 to connect the brake pipe 18, through cavity 29, with exhaust port 30.

Fluid under pressure will then be vented 30 from the brake pipe 18 to thereby cause an application of the brakes in the well known manner and the consequent reduction in the speed of the train.

When the speed of the train has been reduced to a predetermined degree, the governor balls 24 will collapse, so as to permit the stem 26 to move the contact 27 and close the circuit of the magnet device 4. The energization of said magnet device then operates to close the valve 19.

Fluid pressure from valve chamber 15 then equalizes into piston chamber 13, through port 31 in piston 14, permitting the spring 32 to shift the piston 14 and slide 45 valve 17 to normal position, in which the brake pipe 18 is cut off from the exhaust port 30.

The brake pipe pressure can then be increased to release the brakes and thereby 50 permit the train to proceed at a speed less than the speed at which the governor device 3 operates to open the magnet circuit.

The governor device 3 may be directly connected to the axle of the vehicle, so that 55 there will be little danger of failure of this governor.

By the operation of the above described construction, the train speed is prevented from exceeding a predetermined degree in 60 case the speed governor should fail, and the train speed is reduced, if the failure occurs while the train is running at a speed exceeding the predetermined low speed at which this construction is adjusted to operate.

65 Having now described my invention, what

I claim as new, and desire to secure by Letters Patent, is:—

1. In a train speed control apparatus, the combination with a governor device responsive to the train speed for regulating the speed of the train, of means operative upon failure of the governor device for limiting the speed of the train. 70

2. In a train speed control apparatus, the combination with a governor device responsive to the train speed for regulating the speed of the train, of means operative at a train speed exceeding a predetermined degree, upon failure of the governor device, for limiting the speed of the train. 75

80 3. In a train speed control apparatus, the combination with a governor device responsive to the train speed for regulating the speed of the train, of a valve device operated by a variation in fluid pressure for effecting an application of the brakes, and valve means operated upon failure of said governor device for varying the pressure on said valve device.

4. In a train speed control apparatus, the combination with a governor device responsive to the train speed for regulating the speed of the train, of a valve device operated by a variation in fluid pressure for effecting an application of the brakes, a valve 95 operated upon failure of said governor device for varying the fluid pressure on said valve device, and a valve operated according to the speed of the train for controlling communication through which the fluid pressure 100 on said valve device is varied.

5. In a train speed control apparatus, the combination with a governor device operated according to the speed of the train for regulating the speed of the train, of a valve 105 device operated upon a reduction in fluid pressure therein, for effecting an application of the brakes, a valve operated by said governor device upon failure of same for venting fluid pressure from said valve device, 110 a valve for controlling communication through which fluid is vented from said valve device, and a governor device operated according to the speed of the train for controlling said valve. 115

6. In a train speed control apparatus, the combination with a governor device operated according to the speed of the train for regulating the speed of the train, of a valve device operated upon a reduction in fluid pressure therein, for effecting an application of the brakes, a valve operated by said governor device upon failure of same for venting fluid pressure from said valve device, 120 a valve for controlling communication through which fluid is vented from said valve device, a magnet for operating said valve, and a governor device operated according to the speed of the train for controlling the circuit of said magnet. 125

7. In a train speed control apparatus, the combination with a governor device operative according to the train speed for regulating the speed of the train, of means operative upon failure of the governor device for effecting a reduction in the speed of the train, a governor device operated according to the speed of the train, and a device controlled by said governor device and operative to prevent the operation of said means at a train speed less than a predetermined degree.
- 5 In testimony whereof I have hereunto set my hand.

THOMAS H. THOMAS.
